UNITED STATES PATENT OFFICE

JOHN C. ZIPPERER, OF EVANSTON, ILLINOIS

POWER DRIVEN MORTISING TOOL

Application filed October 8, 1932. Serial No. 636,065.

This invention relates to a portable power driven rotary tool expressly designed for boring and mortising timbers used in constructional work.

5 In developing and perfecting the structure, it has been my primary aim to provide a novel and practical assembly of parts properly co-ordinated to provide a self-contained prime mover or power unit carried 10 by an adjustable carriage mounted on an adjustable base, whereby to permit the requisite relative adjustment of parts necessary for expeditious and efficient work.

One feature of the invention is found in 15 the particular construction of a two-part base wherein the lower part has adjustable clamping means for attachment directly to the work, the upper part being laterally adjustable, that is, at right angles to the longitudinal dimension of the work in order to properly position the carriage.

Another feature of the invention is predicated upon the specific construction and location of the carriage, said carriage being 20 longitudinally adjustable on the movable upper part of the base, whereby to permit the carriage to be centrally located and then intermittently shifted longitudinally in order to provide a recess in the work of appropriate shape and proportion.

Other features and advantages of the invention will become more readily apparent from the following description and drawings.

35 In the drawings:

Figure 1 is an elevation, with parts in section, of the complete machine, the section being taken on the line 1—1 of Figure 2.

40 Figure 2 is a front end elevation of Figure 1, that is, a view observing Figure 1 in a direction from right to left.

Figure 3 is a top plan view of Figure 1.

45 Figure 4 is a top plan view of the lower clamp-equipped part of the base.

Figure 5 is a transverse vertical sectional view taken on the plane of the irregular line 5—5 of Figure 1.

50 Figure 6 is a similar sectional view taken on the line 6—6 of Figure 1.

Figure 7 is a section on the line 7—7 of Figure 4.

Figure 8 is a fragmentary detail elevational view.

Figures 9 and 10 are sections on the lines 55 9—9 and 10—10 respectively of Figure 2.

Referring first to the complete invention depicted in Figure 1, it will be observed that the work (a piece of timber) is generally denoted by the numeral 11, the recess therein 60 being distinguished by the numeral 12. As before implied, the machine is of a portable nature and is adapted to be detachably clamped to the work. Thus I provide a 65 novel clamp-equipped adjustable base comprising upper and lower parts or units 13 and 14 respectively.

As shown in Figure 4, the lower part 70 comprises a pair of I-shaped tracks 15 disposed in spaced parallelism and adapted to extend transversely across the work, these tracks being joined together through the medium of a connective web 16 of the style shown, said web being formed at its center with a fixed feed nut 17.

In cross section, the tracks 15 are of hollow channeled formation and provided at 75 opposite ends with bearings 18 (see Figure 5) to accommodate the smooth journal forming ends of an adjusting screw 19 for the work engaging jaws 20. Incidentally the screw is provided with right and left threads for adjusting the jaws toward and from 80 each other and the jaws are fashioned with retention hooks 21 (see Figure 7) engageable 85 slidably with the track flanges.

As shown in Figure 2, a hand crank 22 is attachable to each feed screw 19 for convenient regulation of the clamping jaws. Referring again to Figure 1 it will be observed 90 that the upper relatively adjustable part or unit 13 of the base is of general U-shaped form and embodies a pair of end members 23 joined together by longitudinal side members 24.

Intermediate their ends the side members 95 are formed with upstanding lugs 25 constructed to provide bearings for the shifting screw 26 (see Figure 6), whose threaded portion is threaded through the aforesaid 100

feed nut 17. Again, a hand crank 27 is provided for convenient adjustment of this particular feed screw.

The unit 13 is slidably coupled to the 5 tracks 15 through the medium of coupling shoes 28 as plainly indicated in Figure 1. This allows the entire unit 13 to be adjusted transversely of the work 11, that is, with respect to the relatively stationary part 14 10 of the base.

Attention is now called to the numerals 29 which designate horizontally disposed spaced parallel bars mounted in the end members 23 and formed at one end with 15 rack teeth 30. The numeral 31 designates a stop collar carried by one of the rack bars and held in place by a set screw 32. Attached to this collar is a gauge rod 33 provided with a stop collar 34 surrounding the 20 toothed portion of the rack bar.

These rack bars 29 serve to adjustably support the longitudinally adjustable tool and prime mover carriage 35. This carriage comprises a plate 36 on which a gasoline 25 motor or equivalent power plant 37 is mounted, said plate being provided with depending legs 38 slidable along the rack bars. Attached to the outer pair of legs are brackets 39 formed with bearings for a rotary 30 shaft 40 carrying pinions 41 in mesh with the rack teeth. The shaft is provided with a crank 42 for convenient adjustment of the carriage as a unit.

Attached to the carriage and forming a 35 part thereof are horizontal spaced parallel rails 43 to the outer ends of which a frame 44 is connected. Incidentally the numerals 45' merely designates braces for the frame and as shown in Figure 2 this frame is provided with upper and lower guides 45 and 46 for the rotary tool shaft 47. The shaft is turned through the instrumentality of a bevelled gear 48 receiving power from a bevelled pinion 49 mounted on an adjacent 45 shaft 50 journalled in a suitable bearing 51 and operated by a pulley 52. The pulley receives power by way of a belt 53 trained thereover and also over a companion pulley 54 with which the motor 37 is provided as 50 shown in Figure 1.

The numeral 55 in Figures 2 and 9 designate a lever for engaging and disengaging the bevelled pinion 49 which lever is mounted on an extension 56 as shown in Figure 9 55 and held in adjusted position by a set screw 57. Detachably connected to the lower end of the tool shaft 47 is the boring or mortising tool 58 and mounted on the upper portion of the tool shaft is a regulating stop collar 59 60 for regulating the depth of the recess in the work as is obvious. Incidentally, any type of tool head 58 may be used for boring and mortising the work.

In practice, the lower relatively stationary 65 section 14 of the base is clamped to the work

11 through the intermediacy of the clamping jaws 20 as shown in Figure 5. As before stated, these jaws are adjusted conveniently by proper manipulation of the handcranks 22. Then the upper relatively adjustable section 13 of the base is shifted transversely with respect to the longitudinal dimension of the work through the medium of the adjusting screw 26 and handcrank 27 (see Figure 6). This serves to position the tool shaft 75 over the desired place before the tool is set in operation.

A final adjustment of the tool is made by adjusting the tool carriage 35. This is accomplished as is obvious through the medium of the rack bars 30 and co-operating pinions 41. The shaft 40 with its handcrank 42 permits this to be conveniently accomplished. Consequently the entire carriage including the motor and tool and associated parts may be bodily shifted when the tool is set into operation and then shifted in a direction from right to left in Figure 1 in order to permit the mortise to be longitudinally elongated. The gauge rod 33 and collar 34 is convenient in permitting the carriage to be accurately located for uniformity of work, that is, where timbers of like sizes require corresponding mortising.

It will be noted that the base is of a versatile nature in that it may be adapted to timbers of different proportions. It may be firmly clamped in place and readily detached to take advantage of the portability of the entire machine. After the part 14 is once clamped in place, the relatively adjustable part 13 may be initially adjusted and subsequently adjusted during the operation of the tool to permit the tool to be properly located as conditions may require. Then too, the adaptability of the carriage 35 whereby it may be individually adjustable in a longitudinal direction adds to the practicability and utility of the structure in order that it may serve adequately in fulfilling the expected 100 requirements and results.

It is probably unnecessary to say that the prime mover 37 may be either an electric motor or a gasoline engine whichever is desirable. Since the instant style and type of machine is primarily adapted for farm use, the gasoline engine power plant seems to be in demand.

It is thought from the foregoing description that the advantages and novel features of the invention will be readily apparent.

It is to be understood that changes may be made in the construction and in the combination and arrangement of the several parts provided that such changes fall within the scope of the appended claims.

I claim:

1. A structure of the class described comprising a two-part base, the lower part of said base embodying spaced parallel tracks

having bearings formed at their opposite ends, a web connecting said tracks together in spaced parallelism, said web being formed with a central feed-nut, a pair of feed screws journalled for rotation in the bearings of said tracks, work engaging and clamping jaws slidably mounted on the tracks and operatively connected with said feed screws, the upper part of the base comprising a substantially U-shaped structure including vertical end members joined together by horizontal side members, said side members being formed with bearings located in alinement with said feed nut, a feed screw operable in said nut and journalled in said bearings, and a hand crank for adjusting said feed screw.

2. A structure of the class described comprising a two-part base, the lower part of said base embodying spaced parallel tracks having bearings formed at their opposite ends, a web connecting said tracks together in spaced parallelism, said web being formed with a central feed-nut, a pair of feed screws journalled for rotation in the bearings of said tracks, work engaging and clamping jaws slidably mounted on the tracks and operatively connected with said feed screws, the upper part of the base comprising a substantially U-shaped structure including vertical end members joined together by horizontal side members, said side members being formed with bearings located in alinement with said feed-nut, a feed screw operable in said nut and journalled in said bearings, and a handcrank for adjusting said feed screw, a pair of spaced parallel horizontally disposed rack bars carried by the vertical end members of said base unit, coupling shoes slidably joining said upper part to said tracks, a tool and motor carriage slidably mounted on said rack bars and provided with pinions operatively connected with the rack bars for the purpose stated.

3. In a structure of the class described, a frame including track members, a pair of depending jaws slidably arranged on each track member, a screw shaft carried by each track member and having oppositely arranged threads thereon and the jaws having threaded holes therein through which the shaft passes, means for rotating the shafts to operate the jaws, a nut member carried by the frame, a second frame, shoes depending from the second frame and engaging the track members, a screw shaft rotatably arranged in the second frame and passing through the nut of the first frame, means for rotating the last mentioned shaft for adjusting the second frame on the first frame.

4. In a structure of the class described, a frame including track members, a pair of depending jaws slidably arranged on each

track member, a screw shaft carried by each track member and having oppositely arranged threads thereon and the jaws having threaded holes therein through which the shaft passes, means for rotating the shafts to operate the jaws, a second frame, shoes depending therefrom for slidably engaging the track members, manually operated means for moving the second frame on the track members, a pair of parallel rack bars supported from the upper part of the second frame, a carriage slidably mounted on said rack bars, a shaft rotatably supported by the carriage, pinions on the shaft engaging the rack teeth of said bars, a handle for rotating the shaft, a tool carried by the carriage, a motor carried by the carriage and means for operating the tool from the motor.

In testimony whereof I affix my signature. 85

JOHN C. ZIPPERER.
